(57) **CLAIM**

I claim the ornamental design for a nasal dilator, as shown and described.

DESCRIPTION

FIG. 1 is an isometric view of a first embodiment of a nasal dilator shown with a first environment;

FIG. 2 is a top view of the nasal dilator of FIG. 1 shown with a first environment;

FIG. 3 is a bottom view of the nasal dilator of FIG. 1;

FIG. 4 is a right side view of the nasal dilator of FIG. 1, the left side view being a mirror image thereof;

FIG. 5 is a front elevation view of the nasal dilator of FIG. 1;

FIG. 6 is a rear elevation view of the nasal dilator of FIG. 1; FIG. 7 is an isometric view of a second embodiment of a nasal dilator shown with a first environment, the bottom, right side and its mirror image left side, front elevation, and rear elevation views being identical to the corresponding views illustrated for the first embodiment;

FIG. 8 is a top view of the nasal dilator of FIG. 7 shown with a first environment;

FIG. 9 is an isometric view of the nasal dilator shown in FIG. 1 shown with a second environment;

FIG. 10 is a top view of the nasal dilator of FIG. 1 shown with a second environment;

FIG. 11 is a right side view of the nasal dilator of FIG. 1 shown with a second environment, the left side view being a mirror image thereof;

FIG. 12 is a front elevation view of the nasal dilator of FIG. 1 shown with a second environment;

FIG. 13 is a rear elevation view of the nasal dilator of FIG. 1 shown with a second environment;

FIG. 14 is an isometric view of the nasal dilator shown in FIG. 7 shown with a second environment;

FIG. 15 is a top view of the nasal dilator of FIG. 7 shown with a second environment;

FIG. 16 is a right side view of the nasal dilator of FIG. 7 shown with a second environment, the left side view being a mirror image thereof;

FIG. 17 is a front elevation view of the nasal dilator of FIG. 7 shown with a second environment; and,

FIG. 18 is a rear elevation view of the nasal dilator of FIG. 7 shown with a second environment.

The broken lines are directed to environment and form no part of the claimed design.

1 Claim, 4 Drawing Sheets
